CLAIM

The ornamental design for a bottle with cap, as shown and described.

DESCRIPTION

FIG. 1 is a perspective view of the bottle with cap comprising the present invention;

FIG. 2 is a top plan view of the bottle with cap of FIG. 1, on a reduced scale;

FIG. 3 is a side elevational view of the bottle with cap of FIG. 1, on a reduced scale;

FIG. 4 is a front elevational view of the bottle with cap of FIG. 1, on a reduced scale;

FIG. 5 is a side elevational view, opposite the side shown in FIG. 3, of the bottle with cap of FIG. 1, on a reduced scale;

FIG. 6 is a rear elevational view of the bottle with cap of FIG. 1, on a reduced scale; and,

FIG. 7 is a bottom plan view of the bottle with cap of FIG. 1, on a reduced scale.
